CITRUS JUICE EXTRACTOR

Wilma M. Schiller, 1031 W. Lake Cannon Drive,
Winter Haven, Fla. 33880

Filed Sept. 19, 1967, Ser. No. 8,651

Term of patent 14 years

U.S. Cl. D89—1
Int. Cl. D7—05

FIG. 1.

FIG. 4.

FIG. 2.

FIG. 3.

The glass shown in broken lines in FIGURES 1 and 4 is for illustrative purposes only.

I claim:

The ornamental design for a citrus juice extractor, as shown and described.
